UNITED STATES PATENT OFFICE.

DONALD BAXTER MACMILLAN, OF FREEPORT, MAINE.

HEATER.

Application filed January 24, 1921. Serial No. 439,438.

To all whom it may concern:

Be it known that I, DONALD B. MACMILLAN, a citizen of the United States, residing at Freeport, county of Cumberland, State of Maine, have invented certain new and useful Improvements in Heaters, of which the following is a specification.

This invention relates to heating apparatus and more particularly to a heating device for converting ice or snow into hot water.

In field work in northern regions or at high altitudes or in seasons of extreme cold the only available source of supply of pure water is ice or snow and in many instances it is of paramount importance to obtain quickly hot or boiling water without delay from such congealed sources.

The problem of obtaining hot or boiling water from such a source by apparatus capable of transportation as field equipment is further rendered difficult by the almost imperative necessity that the change from the congealed form to the hot liquid form be accomplished in a very short time. This requirement is based on the stern necessity of conservation of time and of emergency use under conditions which do not permit exhausted and famished men to wait for any slow process of melting and subsequent boiling for the purposes of the preparation of food or drink.

In arctic work, particularly in more recent years, various devices have been tried with greater or less degree of success. Such devices have been for the most part rather crude and experimental. While they have operated with sufficient success to demonstrate the principle, they have not been made mechanically adequate or of proper convenience or efficiency.

The general principle involved was originally conceived by the late Admiral R. E. Peary and no claim is herein made as to the originality of said general principle. This principle above acknowledged was briefly that the action of heat whether from hot fumes or flames might be applied direct to a mass of ice fragments or chunks of snow around a centrally disposed kettle or pot which should catch the drip of the melting ice and be itself heated so as to boil the water as it accumulated in the pot.

As illustrative of my invention I have

shown in the accompanying drawing an embodiment which in part has been found of proven utility in the field and in part an improvement and refinement developed in field experience. I shall discuss this embodiment therefore both as illustrative of the features of my invention and as in itself constituting a form well adapted to practical use. Throughout the specification and drawings like reference characters are employed to indicate corresponding parts, and in the drawings:

Fig. I is an external view of a stove in accordance with my invention and with the parts separated.

Fig. II an external view of the stove assembled.

Fig. III a view of the stove packed for shipment.

Fig. IV is a sectional view of the stove assembled.

Fig. V a sectional view of the stove packed.

Fig. VI is a bottom view of the container section as seen from the indicated line of vision VI—VI, Fig. I, and

Fig. VIII is a fragmentary section on the line VII—VII of Fig. V looking down.

My stove consists primarily of an upper or ice chamber section 1 and a lower or hot water section 2, each of said sections being preferably cylindrical. The upper section 1 preferably has an outside bearing on the top of section 2 when in use and slips over and encloses the section 2 when inverted thereon, so as to pack snugly and conveniently and form a suitable container for such mess kits or provisions as may be desired to be packed therein.

The section 1 consists of a simple cylindrical shell or body having near its lower end a bottom 10 formed as an inverted cone, the apex of which extends substantially to but not beyond the lower end of the external shell. This bottom is perforated as at 10¹ and constitutes a support for a mass of ice fragments 1 or the like, the apex or point constituting a central drip to which the water tends to trickle as the ice melts.

The upper portion 1 has a suitable cover 13 having an internal flange 13¹ and a handle or strap loop 13² and the sides of the body 1 are provided with strap guides 1¹.

The bottom portion consists also of a tu-

bular shell 2 in which is supported a kettle or water container 21. This container is perforated around its margin with openings 22 through which fumes from an annular lamp 23 may pass upwardly into the ice chamber.

10 The bottom of the kettle 21 is slightly concaved as at 21¹ forming a slight air pocket in which heat tends to accumulate and centralize before passing to the openings 22, so that the heat after passing the margin of the pocket 21² is distributed about the surface of the pan 21 and lead with more or less directness to the openings 22.

15 The burner 23 is preferably a simple annular trough of suitable diameter to give proper distribution of heat over the bottom of the pan 21 and of sufficient capacity to hold a predetermined amount of alcohol or 20 other liquid fuel sufficient to melt ice to fill the kettle 21. The fuel is preferably alcohol. The burner 23 may be mounted in any convenient manner but is conveniently attached to the inner face of the lower cover 25 24. The cover 24 has an internal flange 24¹ pierced for draft at 28. This cover is preferably insulated as at 25 so that where the stove is set on the snow or ice it will not melt away its own support. The covers 13 30 and 24 are both provided with bayonet lock connections 26 with their respective shells so that when packed the stove is held together and may be used as a container.

35 In operation when the stove is set up as shown in Figs. II and IV, the upper reservoir is filled with chunks or fragments of ice or if snow is used it should be compressed into chunks or balls to permit draft through the ice chamber. With the lamp 23 lighted, 40 water almost immediately begins to drip from the apex of the conical bottom 10 into the kettle 21 and almost immediately the accumulating water begins to boil. As the play of the heat is directly on the kettle 21 45 it is maintained hot and the water is heated as it accumulates. In practice in about nine minutes a gallon of boiling water may be produced from ice at 60° F. so that by the time the ice is completely melted the pan 21 50 is filled with boiling water.

At this point the upper portion 1 is lifted from the lower portion and the contents of the pan 21 may be dipped out with cups or if desired may be poured into other receptacles. For the purposes of pouring I omit the draft holes 22 for a short space on the margin of the kettle 21 as at 21¹, Figs. IV 55 and V.

60 When it is desired to pack the stove the cover 13 of the top 1 is removed and the top 1 inverted and slid down over the base 2 and the cover 13 applied to the opposite end of the section 1.

65 The end closure 24 provided for the bottom of the portion 1 is provided with a flat

strap opening 24² so that when the upper portion is inverted and the stove shoved together in telescope position, a strap or thong may be passed about it, holding the parts together and also providing a tight container in which food or supplies may be contained. The upper section 1 is of sufficient length to close the openings 28 when the stove is packed for shipment. This prevents the loss of any small articles of food 70 or equipment packed within the stove.

75 The stove may be conveniently built of light thin sheet iron or other metal so that it is strong and durable and yet sufficiently light to avoid being a burden even under the most adverse conditions.

80 Various modifications may of course be made in the construction and arrangement of parts of my apparatus and in the manner of assembly and details of design, all without departing from the spirit of my invention if within the limits of the appended claims.

85 What I therefore claim and desire to secure by Letters Patent is:

90 1. A heater comprising a heater section and a reversible container section telescopically mounted thereon, an open-top kettle mounted within said heater section, there being a space between the walls of the kettle and the heater section to permit the circulation of heated air about the kettle, said container section having a perforated bottom extending into the open top of said kettle when the heater is set up for use and constituting a cover for said kettle when the container section is reversed upon said heater section for purposes of transportation, and a heater disposable beneath said kettle.

- permit the circulation of heated air about and into the kettle through the heat admission openings, said container section having a perforated inverted conic bottom extending into the open top of said kettle when the heater is set up for use and constituting a cover for said kettle when the container section is reversed upon said heater section for purposes of transportation, and 5 a heater disposable beneath said kettle. 10
4. A heater comprising a heater section, an open-top kettle disposed within and connected at its upper edge to said heater section and having heat admission openings 15 through the upper part of its wall, there being a space between the kettle and the heater to permit the circulation of heated air about and into the kettle through said heat admission openings, and a heater disposable 20 beneath and a container section disposable above said kettle. 25
5. A heater comprising a heater section having a draft opening, an open-top kettle mounted within said heater section, a container section telescopically mounted upon said heater section and having a perforated bottom extending into the open top of said kettle when the heater is set up for use and constituting a cover for said kettle when 30 the container section is reversed upon said heater section for purposes of transportation and said container section when reversed itself closing said draft opening of the heater section, and a heater disposable 35 beneath said kettle. 40
6. A heater comprising an open-bottom heater section having a draft opening adjacent its bottom; an open-top kettle mounted within said heater section, there being a space between the walls of the kettle and the heater section to permit the circulation of heated air about the kettle, an open-top container section telescopically mounted upon said heater section and having a perforated downwardly disposed bottom extending into the open top of said kettle when the heater is set up for use and constituting a cover for said kettle when the container section is reversed upon said heater section 45 for purposes of transportation and said container section when reversed itself closing said draft opening of the heater section, removable closures for said heater and container sections, and a heater disposable beneath said kettle and supported upon the bottom closure for the heater section. 50
7. A heater comprising an open-bottom heater section, a closure therefor having a draft opening, an open-top kettle mounted 55 within said heater section and having heat admission openings through the upper part of its wall, there being a space between the walls of the kettle and the heater section to permit the circulation of heated air about and into the kettle through said heat ad-
- mission openings, an open-top container section telescopically mounted upon said heater section and having a perforated inverted conic bottom extending into the open top of said kettle when the heater is set up 70 for use and constituting a cover for said kettle when the container section is reversed upon said heater section for purposes of transportation and said container section when reversed itself closing said draft opening in the bottom closure for the heater section, a heater disposable beneath said kettle, and a removable closure for the open top of said container section. 75
8. A heater comprising an open-bottom heater section, a removable closure for the bottom of said section and having a draft opening, an open-top kettle connected at its upper edge to said section and extending downwardly thereto, there being a space 80 between the walls of the kettle and heater section to permit the circulation of heated air about the kettle, and having adjacent its top edge a plurality of heat admission passages and a heat centralizing pocket in its bottom wall, a heater mounted upon said closure immediately below said heat centralizing pocket, an open top container section telescopically mounted upon said heater section and having a downwardly disposed bottom extending into the open top of said kettle when the heater is set up for use and constituting a cover for said kettle when said container section is reversed upon said heater section for purposes of transportation 85 and said container section when reversed itself closing said draft opening at the bottom of the heater section, and a removable closure for the open top of said container section. 90
9. A heater comprising an open-bottom heater section, a removable closure for the bottom of said section and having a draft opening, an open-top kettle extending downwardly into said section and having a heat centralizing pocket in its bottom wall, a heater mounted upon said closure immediately below said heat-centralizing pocket, an open top container section telescopically mounted upon said heater section and having a perforated inverted conic bottom extending into the open top of said kettle when the heater is set up for use, and constituting a cover for said kettle when said container section is reversed upon said heater section for purposes of transportation 95 and said container of a length to close said draft opening at the bottom of the heater section when reversed upon said heater section, and a removable closure for the open top of said container section. 100
10. A heater comprising a heater section bent upon itself at its upper edge to provide an open-top kettle extending downwardly into said section in spaced relation thereto, 110
11. A heater comprising a heater section 115 bent upon itself at its upper edge to provide an open-top kettle extending downwardly into said section in spaced relation thereto, 120
12. A heater comprising a heater section 125 bent upon itself at its upper edge to provide an open-top kettle extending downwardly into said section in spaced relation thereto, 130

4

said kettle having adjacent its top edge a plurality of heat admission passages and having a heat-centralizing pocket in its bottom wall, a heater mounted within said 5 heater section immediately below said heat-centralizing pocket, and a container section disposable above said kettle.

In testimony whereof I affix my signature in presence of two witnesses.

DONALD BAXTER MACMILLAN.
